CLAIM

The ornamental design for a vapor recovery fuel nozzle deflector, as shown and described.

DESCRIPTION

FIG. 1 is a rear perspective view of the vapor recovery fuel nozzle deflector showing our new design;

FIG. 2 is a side view thereof with the opposite side being a mirror image thereof;

FIG. 3 is a front elevational view thereof;

FIG. 4 is a rear perspective view thereof;

FIG. 5 is a top plan view thereof; and,

FIG. 6 is a bottom view thereof.
